UNITED STATES PATENT OFFICE.

CLAUDE S. HOPKINS, OF DAYTON, OHIO.

COUCH FABRIC.

1,276,919.

Specification of Letters Patent. Patented Aug. 27, 1918.

Application filed November 30, 1917. Serial No. 204,583.

To all whom it may concern:

Be it known that I, CLAUDE S. HOPKINS, a citizen of the United States, residing at Dayton, in the county of Montgomery and 5 State of Ohio, have invented certain new and useful Improvements in Couch Fabrics, of which the following is a specification.

My invention concerns improvements in 10 metallic couch or bed-bottom fabrics, and pertains more especially to those of the articulated wire type, ordinarily resiliently fastened to the supporting frame by helical springs. The prime object of the present 15 invention is the production of a structure of this general character which will be strong, simple in structure, economical to manufacture, easy to assemble, and which may be shipped and transported in compact form without difficulty.

Another feature of the invention is the provision of an appliance of this type in which single-strand wire elements are employed, and in which the cross-links are 25 effectively held against displacement longitudinally of the structure.

In order that those skilled in this art may have a full and complete understanding of 30 this invention and its various advantages, I have illustrated a preferred embodiment of the same in the accompanying drawings to which reference should be had in connection with the following detailed description of the construction, and throughout the 35 various views of which like reference characters refer to the same parts.

In the drawing:

Figure 1 is a partial plan view of the structure;

Fig. 2 is an elevation of the same, and

Fig. 3 is a fragmentary perspective view showing the manner of attaching the cross-links to the lengthwise members of the fabric.

Referring to the drawing, it will be clear 45 that the longitudinal elements of the fabric comprise a plurality of single-strand lengths of wire 10 extending from end to end of the structure with their terminal portions 50 securely fastened by means of the usual helical or spiral springs 11 to the frame 12. At equal intervals each of these lengthwise wires is laterally kinked or deflected at 13 to afford convenient means for the effective 55 connection of the cross-links 14, the kinks of the various wires being in straight rows

crosswise of the fabric. Each single-strand wire cross-link has a downturned hook or loop-shaped end 15 engaging the kinked or bent portion of one of the longitudinal members 10, and at its other end each cross-link is bent to form a double-loop or bifurcated portion 16, 17, engaging the next adjacent lengthwise wire 10 on opposite sides of the corresponding kink thereof, and, of course, necessarily on opposite sides of the hook-end of another adjacent cross-link coöperating with such kink. Stated somewhat differently, each cross-link is bent around the lengthwise wire 10 at each side of a kink 13 to provide a loop or eye 16 at an obtuse angle to the main body of the link, and is then bent around the same wire 10 at the opposite side of the kink to form a second loop or hook at another obtuse angle to 75 the length of the cross-link; these two loops or eyes forming a bifurcated or divided end for the cross-link. As is clearly shown, the kink of wire 10 and the pair of loops of the cross-link form a horizontal substantially square closed eye or aperture into which the downturned hook-end of the next cross-link fits. The angle of the kinks is such that the double or divergent loops of the cross-links can not slide along the wires 85 10 and, consequently, they prevent the hook-ends 15 of the transverse links from sliding along the lengthwise wires and thus becoming displaced. The metallic fabric can be 90 readily folded for transportation and without danger of its parts becoming entangled, because the cross-links, while capable of a hinging action on the longitudinal wires 95 10, are prevented from shifting thereon out of their proper places.

It should be clear to those skilled in this art that many minor mechanical changes may be made in the structure presented without departure from the substance of the invention and without the sacrifice of 100 any of its substantial benefits, and it will be appreciated, that, in the device disclosed in this application, by making the various members comprising the fabric of a single length or strand of wire, the fabric can be 105 constructed at a minimum of expense and can yet be so made as to afford sufficient strength for all ordinary purposes.

I claim:

1. In a couch-fabric construction, the 110 combination of a plurality of longitudinal members kinked at intervals, and cross-links

each having an end portion engaging one of said kinks and an opposite end portion straddling the corresponding kink of an adjacent longitudinal member, substantially as described.

2. In a couch-fabric construction, the combination of a plurality of single-strand longitudinal members kinked at intervals, and cross-links having an end portion engaging one of said kinks and an opposite end portion straddling the corresponding kink of an adjacent longitudinal member, substantially as described.

3. In a couch-fabric construction, the combination of a plurality of single-strand longitudinal members kinked at intervals, and single-strand cross-links each having an end portion engaging one of said kinks and an opposite end portion straddling the corresponding kink of an adjacent longitudinal member, substantially as described.

4. In a couch-fabric construction, the combination of a plurality of single-strand longitudinal members continuous from end to end of the fabric and kinked at intervals, and single-strand cross-links each having an end portion engaging one of said kinks and an opposite end portion straddling the corresponding kink of an adjacent longitudinal member, substantially as described.

5. In a couch-fabric construction, the combination of a plurality of single-strand longitudinal members kinked laterally at intervals, and cross-links having an end portion engaging one of said kinks and an opposite end portion straddling the first-mentioned end portion of a companion cross-link engaging the kink of the adjacent longitudinal cross-member, substantially as described.

6. In a couch-fabric construction of the character described, the combination of a plurality of single-strand longitudinal members continuous from end to end of the fabric and kinked laterally at intervals, and single-strand cross-links, each having an end portion engaging one of said kinks and an opposite end portion straddling the first-

mentioned end portion of a companion cross-link engaging the kink of the adjacent longitudinal member, substantially as described.

7. In a couch-fabric construction of the character described, the combination of a plurality of spaced longitudinal members and associated single-strand cross-links, each of the latter engaging one of said members at one end and bent at its other end to provide two spaced loops both engaging a companion longitudinal member, substantially as described.

8. In a couch-fabric construction of the character described, the combination of a plurality of spaced longitudinal single-strand members and associated single-strand cross-links, each of the latter engaging one of said members at one end and bent at its other end to provide two divergent loops both engaging a companion longitudinal member, substantially as described.

9. In a couch-fabric construction of the character described, the combination of a plurality of spaced single-strand longitudinal members and associated single-strand cross-links, each of the latter being bent around one of said members at one end and bent at its other end to provide two spaced loops both engaging a companion longitudinal member on opposite sides of the first-mentioned end of an adjacent cross-link, substantially as described.

10. In a couch-fabric construction of the character described, the combination of a plurality of spaced longitudinal single-strand members kinked laterally at intervals, and associated independent single-strand cross-links, each of the latter engaging one of the kinks of said members at one end and bent at its other end to provide two spaced loops both engaging a companion longitudinal member on opposite sides of the first-mentioned end of an adjacent cross-link coöperating with one of the kinks, substantially as described.

CLAUDE S. HOPKINS.
